CLAIM

The ornamental design for a foldable and convertible creeper, as shown and described.

DESCRIPTION

FIG. 1 is a left side elevational view of the foldable and convertible creeper showing my new design, in its extended condition with the seat folded.

FIG. 2 is a right side elevational view thereof;

FIG. 3 is a front end elevational view thereof;

FIG. 4 is a rear end elevational view thereof;

FIG. 5 is a top plan view thereof;

FIG. 6 is a bottom plan view thereof;

FIG. 7 is a left, front perspective view thereof, in folded condition, with the seat folded.

FIG. 8 is a left, front perspective view thereof, in folded condition, with the seat extended.

FIG. 9 is a right, rear perspective view thereof, in folded condition, with the seat folded.

FIG. 10 is a right, rear perspective view thereof, in folded condition, with the seat extended.
